UNITED STATES PATENT OFFICE.

CATHERINE O'HARA, OF NEW YORK, N. Y., ASSIGNOR TO THE BUTTERICK PUBLISHING CO., (LIMITED,) OF SAME PLACE.

DESIGN FOR A CHILD'S CLOAK.

SPECIFICATION forming part of Design No. 14,364, dated October 23, 1883.
Application filed August 23, 1883. Term of patent 3½ years.

To all whom it may concern:

Be it known that I, CATHERINE O'HARA, of the city, county, and State of New York, have invented and produced a new and original Design for a Pattern of a Child's Cloak, (numbered 8,857;) and I do hereby declare that the engraved prints accompanying this specification convey to any one accustomed to using paper patterns a clear understanding of how to a garment made up by the pattern will appear.

The design combines a yoke-top, a lower part box-plaited at the front and back, a deep

shirred collar, and coat-sleeves, the collar having one tuck and the lower part two tucks 15 near their lower edges.

What I claim as my invention, and desire to secure by Letters Patent, is—

The design for a child's cloak, as shown in the engraved prints accompanying this specification.

CATHERINE O'HARA.
